CARRYING CARTON FOR SPRINKLER HOSE OR THE LIKE

Robert F. Bond and Walter W. Felts, Denver, Colo., as signors to The Gates Rubber Company, Denver, Colo., a corporation of Colorado

Application February 1, 1956, Serial No. 39,988

Term of patent 7 years

(Cl. D58—2)

FIG. 1.

FIG. 3.

FIG. 2.

Fig. 1 is a front elevation of a carrying carton for a sprinkler hose embodying our new design;

Fig. 2 is a rear elevation thereof; and

Fig. 3 is a side elevation thereof.

The dominant features of our design reside in the portions shown in full lines.

We claim:

The ornamental design for a carrying carton for sprinkler hose or the like, as shown and described.
